UNITED STATES PATENT OFFICE

ALVA EMERY GREGORY, OF OKLAHOMA CITY, OKLAHOMA

ADJUSTMENT TABLE

Application filed July 29, 1924. Serial No. 728,944.

The present invention has for its purpose to provide, in an adjustment table to be used by chiropractors, osteopaths and physicians in the treatment or adjustment of patients, unitary means for facilitating the adjustment of the opposite end portions of the table in opposite directions, either toward or away from each other, so that the table may be properly proportioned in order to facilitate the manipulation of the body of the patient.

Another purpose is to provide an adjustment table embodying improvements on the construction of similar apparatus disclosed in Letters Patent No. 1,280,987, issued October 8, 1918, to Alva E. Gregory.

Still another purpose is to provide improved means for supporting the patient without unnecessary pain or discomfort, provision being made to accommodate large ab-
domens, especially at the time of treating the body, especially the limbs thereof. In the patent above mentioned, certain of the sections of the adjustment table are capable of adjustment to different positions by hand but in the present invention it is the aim to avoid such an impractical method.

As in the former patent, the present construction of adjustment table is used for treating the patient in such manner as to overcome the settling of the spine of the patient and the consequent thinning of the intervertebral disks which comes on with age, and to overcome any contraction of the spinal musculature from direct spinal injury or reflex contraction due to peripheral injuries or irritations.

It is to be understood that the particulars herein given are in no way limitative and that, while still keeping within the scope of the invention, any desired modifications of detail and desired proportions may be made in the apparatus according to the circumstances.

The invention comprises further features and combinations of parts to be hereinafter set forth, shown in the drawings and claimed.

In the drawings:

Figure 1 is a view in elevation of the improved adjustment table constructed in accordance with the invention.

Figure 2 is a longitudinal sectional view through the same, showing the forward section of the table tilted and the intermediate section partially depressed to accommodate the body of the patient when lying face down.

Figure 3 is a horizontal sectional view on line 3—3 of Figure 2, clearly showing the unitary means for adjusting the remote sections of the table in opposite directions toward and from each other.

Figure 4 is an enlarged perspective view of an extension bracket for the forward end of the forward table section showing an adjustable device to which the head gear may be attached.

Figure 5 is a perspective view of the rear portion of the forward table section and the intermediate table section, showing how the latter is supported on the former.

Figure 6 is a perspective view of the bracket 17 with its casting extension for supporting the worm.

Figure 7 is a sectional view on line 7—7 of Figure 2.

Referring to the drawings, it will be noted that the adjustment table includes a practically skeleton base frame in lieu of the crude base which is disclosed in the former patent, above mentioned. This frame 1 comprises the longitudinal guide tubes 2, the transverse tubular bars 3, and the legs 4, all of which are united at the corners of the base frame by means of the legged unions 5. The legs 4 are footed, as shown at 6. Mounted in perpendicular positions on the guide rails or tubes 2 are forward brackets or supports 7. These brackets or supports are in the form of channel members and their lower terminal parts are formed around the guide rails or tubes 2. The brackets or supports 7 are similar in shape and construction, and connecting the lower terminal loops of the brackets is a bar 8.

The patient supporting table proper 9 comprises the forward, rear and intermediate table sections 10, 11 and 12, the former being pivotally mounted at 13 on the upper terminal portions of the brackets 7. Extending transversely of one end of the forward table section is a rod or shaft 14, and pivoted

thereon are supporting links 15. The lower ends of the links have slots 15^a through which a rod 15^b passes. This rod 15^b is journaled in suitable bearings of the lower 5 portions of the brackets 7, as shown clearly in Figures 2 and 3. Surrounding the rod 15^b and located between the links or arms is a sleeve or tube 15^c. Also mounted on the rod 15^b between the brackets 7 and the links 10 or arms are relatively short sleeves or collars 15^d. The rod 15^b is headed at one end with the head engaging with the outer surface of one of the brackets 7 and the sleeve or collar 15^d opposite the head of the rod engages 15 through the other bracket 7. A suitable hand wheel 16^a is threaded upon the rod 15^b so as to bear against one end of the adjoining sleeve or collar 15^d.

When the sleeves 15^c and 15^d are loose, the 20 arms or links 15 have sliding movements relative to the rod 15^b for the purpose of adjusting the forward table section. For instance, the rear end of the forward table section may be raised or lowered so as to accommodate 25 unusual sizes of abdomens. Should the rear end of the forward table section be raised and the abdomen of the patient be large, it would bear upon the intermediate table section and cause it to lower. With the patient's 30 body in the position shown in Figure 2, the rear end of the forward table section being raised, with a stretching action imparted to the body of the patient, the spinal column may be bowed slightly for the purpose of 35 opening vertebræ, allowing them to be more properly adjusted by chiropractic or osteopathic treatment.

The intermediate table section 12 comprises a metal frame 12^a having an exterior 40 wood molding 12^b, the frame 12^a having a central angular opening 12^c for the reception of an extension of the base portion of a cushion 12^d. The frame 12^a also has an extension arm 13^a which passes between two 45 plates 13^b and 13^c which are supported upon elongated bolts or rods 13^d which depend from the angular frame of the forward table section. In fact, the bolts or rods 13^d pass downwardly through the frame of the 50 forward table section. The extension arm 13^a of the intermediate table section frame 12^a engages between the bolts or rods 13^d. The bolts or rods 13^d pass through closed ends of 55 cylinders 14^a and have pistons or disks 14^b adjustable on their lower ends. These pistons or disks 14^b are located in the cylinders and interposed between them and the closed ends of the cylinders are expansible coil springs 14^c which are in surrounding 60 relation to the bolts or rods 13^d for the purpose of forcing the closed ends of the cylinders upward and retaining the extension arm 13^a in alignment with the rear end of the forward table section. Coil springs 14^d 65 are interposed between the frame of the for-

ward table section and the upper plate 13^b to hold the latter tensioned against the extension arm 13^a. The extension arm 13^a engages under the rod 14.

When the intermediate table section depresses and the rear end of the forward table section tilts upward, the coil springs 14^c are compressed and put under tension. As soon as pressure upon the intermediate table section is relieved, it automatically resumes its 70 normal position.

Also mounted upon the guide rails 2 are brackets or supports 16 and 17, the former being similar in construction to the brackets 7 with the exception that its upper end is enlarged and is fixed to the under portion of the table section 11. The bracket 16 is also mounted on the guide rail in a manner identical with the mounting of the brackets 7. However, the bracket 17 is in the form of a casting, the upper portion of which has a downwardly and laterally projecting extension 17^a which merges into an auxiliary extension 17^b. The extension 17^a has a base plate 17^c to which, as at 19, a suitable electric 80 motor 20 is fastened.

The shaft of the motor 20 is mounted in bearings 20^a of the auxiliary extension 17^b and carries a worm 22 which is located between the bearings 20^a. The lower end of the bracket 17, which supports the table section 11, is adjustably mounted upon one of the guide rails 2 similar to the mounting of the brackets 7, and secured to the lower parts of the brackets 16 and 17 is a frame, 90 comprising the bars 24 and 25, the former being secured to the lower parts of the brackets 16 and 17 while the latter connects the projecting ends of the former.

Pivottally connecting the bars 8 and 25 is 100 a plurality of lazy tong links or bars 26 and rising from certain of the pivotal ends of the lazy tong links or bars and swiveled at 27 to said pivotal ends are upstanding bearings 28 which have right and left threads and 110 through which a screw rod 29 engages. The screw rod 29 is mounted in suitable bearings 30 which rise from the opposite longitudinal guide rails 2. In fact, the bearings 30 are bolted to the rails, so that the screw rod 29 115 may be supported revolvably in position above the lazy tong bars or links.

One end of the screw rod 29 has a hand wheel 31 by which the rod may be rotated and where the rod passes through the bearings or hangers 28, it is provided with right and left threads. Obviously, by imparting movement to the hand wheel in one direction or the other, the screw rod correspondingly 120 operates and due to the right and left threaded connections with the bearings 28, the bearings may move toward and from each other for spreading and contracting the lazy tong links or bars. The act of the lazy tong links or bars contracting and expanding re- 130

sults in the brackets 7 and 16 and 17 and the front and rear table sections being moved toward and from each other in order that the patient may be comfortably accommodated on the table while being subjected to 5 chiropractic or osteopathic treatment.

The table sections 10, 11 and 12 may be constructed in a manner similar to those disclosed in the former patent, and carried by 10 the under portion of the table section 11 are supporting guides 37 for receiving a cast metal extensible frame 38 which, when disposed in the desired position, may be held in such position by means of the set bolt or 15 screw 39. However, when the set bolt 39 is loosened, the extensible frame 38 may be adjusted longitudinally in its supporting guides. Fulcrumly carried at 40 by the rear terminal portion of the frame 38 is an oscillatory lever 41 to the upper terminal of which a casting 42 is connected. This casting consists of a cylinder 32 through the closed end of which a rod 43^a engages, there being a 20 coil spring 43^b interposed between the closed end of the cylinder and a piston or disk 43^c (which is adjustable) for the purpose of tensioning the rod 43^a. The exposed end of the rod 43^a is turned upward and pivotally supports a transverse bar 44^a. The ends of 25 this bar have spaced collars or enlargements 44^b between which the rings of a foot harness 45 may engage.

With the patient disposed as in Figure 2, the head gear being connected to the head of 30 the patient and the foot harness attached to the ankles of the patient, a pulling or stretching action may be imparted to the body of the patient, whereby the patient may be further treated by chiropractic or osteopathic 35 manipulations. When imparting the pulling or stretching action of the body of the patient, the action is gradual which is also true upon relieving the body of the patient of such pulling or stretching action.

The lower terminal portion of the lever 41 40 has a link 46 pivotally connected thereto, said link being, in turn, threaded, as at 46^a, to a rod or pitman 46^b which, in turn, is pivotally connected at 47 to a worm wheel 48. It will 45 be noted that the worm wheel has a plurality of attaching bearings 48^a, in any one of which the pivot pin 47 of the rod 46^b may be secured. In this manner the rod 46^b may be adjusted or pivoted in different locations relative to 50 the worm wheel for the purpose of increasing or decreasing the movement of the lever 41. To permit of this adjustment, the link 46 may be adjusted relative to the rod. The worm wheel 48 is operatively supported on a 55 portion of the auxiliary extension 17^b of the bracket 17 and is so positioned as to mesh with the worm 22.

Obviously, when starting the motor 20 whose shaft imparts revoluble movement to 60 the worm wheel, the wheel will pull upon

the rod 46^b and thereby tilt the lever 41 as may be desired for creating a pull on the foot harness 45 and, in turn, upon the patient at regular intervals in opposition to the resistance of the pulling means at the head 70 and shoulders of the patient. This action has the effect of alternately stretching and relaxing the body gradually, and the amount of stretch may be increased by gradually adjusting the frame 38 in its supporting guides. 75

An extensible bracket 49 is provided and its arm 50 engages in a guide 51, there being a set-screw 52 for holding the extensible bracket in different adjusted positions. Mounted in a bearing at the upper end of the upstanding portion of the bracket 49 is a rod 53 to one end of which a bar 54 is pivotally supported, as at 55. The ends of the bar 54 have spaced collars 56 between which the rings of a head gear or harness 85 57 engage. A suitable hand wheel 58 is threaded to the rod 53 and bears against one end of the bearing at the upper end of the upstanding part of the bracket. By rotating the hand wheel in one direction or the other, 90 the rod 53 may be adjusted through the bearing, either for increasing or decreasing the pulling action upon the head gear or harness. 95

Pivotally supported, as at 59, to lateral ears of the extensible bracket are arms 60 100 95 which diverge for a short distance and are then bent and assume substantially parallel relations and merge into outwardly and upwardly extending portions 61 and 62. The upwardly extending portions 62 are bent inwardly toward the body of the patient at points above the cushion of the forward table section and have knobs at their upper ends. These upwardly extending parts 62 engage under the arm pits of the patient and assist 105 in the pulling action upon the body of the patient.

Any suitable head and foot gear or harness may be employed, for instance, such as that set forth in Patent No. 1,280,987, previously herein mentioned.

In case it should be necessary to adjust or work on the cervical lesions manually and without traction, the head piece or extensible bracket may be removed from its guides, together with the arm pit pieces. 115

The invention having been set forth, what is claimed is:

1. In a device, as set forth, the combination with a lowermost supporting frame, of a pair of guides running lengthwise thereof, a pair of horizontally movable standards moving along the rails of the frame, and said guides, a body supporting table movably mounted upon the upper ends of said guides, a pair of slotted brackets for governing the control of the table in its movements upon the standards, and being slotted, a rod passing through the slots and the standards, means upon the rod to hold the slotted bracket 120 125 130

ets in position of adjustments, a second body-table resiliently and movably mounted with respect to and to the first named body table, means of connection of the slotted brackets to the second named body table, a pair of 5 housings beneath the first named body table, resilient means within the housing for controlling the depression and elevation of the second named body table, with respect to the first named body table, hand grips upon the first named body table and located in fixed position thereto, an adjustable bracket movably mounted to the forward end of the first named body table, an adjustment screw carried by the adjustable bracket at the forward 10 end of the adjustment screw, a head and chin harness carried by the movably mounted lever, means to move the tables aforesaid longitudinally, and a third table to and from 15 which the aforesaid tables are laterally movable, and upon which a portion of the body 20 is sustained.

2. Like 1, adding: a movably mounted foot 25 pulling bracket secured to the third named body supporting table, means for connecting the same to connect the feet of the patient, a worm wheel for the bracket, means to connect the worm wheel to the pulling bracket adjustably for relatively different strokes of the 30 body pulling operation, a worm shaft for the worm wheel, and a motor for the worm shaft.

3. Like 1, adding: said means for moving the body supporting tables consisting of lazy-tongs, and means for extending and contracting said lazy tongs.

In testimony whereof he affixes his signature.
